(57) **CLAIM**

I claim the ornamental design for the tri-slot back, as shown and described.

DESCRIPTION

FIG. 1 is a perspective view of the tri-slot back;
FIG. 2 is a front view of the tri-slot back of FIG. 1;
FIG. 3 is a back view of the tri-slot back of FIG. 1;
FIG. 4 is a side view of the tri-slot back of FIG. 1;
FIG. 5 is a side view of the tri-slot back of FIG. 1 showing the
side opposite that shown in FIG. 4;
FIG. 6 is a top view of the tri-slot back of FIG. 1; and,
FIG. 7 is a bottom view of the tri-slot back of FIG. 1.
